Primary Examiner — W. A. Teddy Falloway*Assistant Examiner* — Melissa A Santos(74) *Attorney, Agent, or Firm* — Thorpe North & Western, LLP(57) **CLAIM**

The ornamental design for a pole mounted lantern as shown and described.

DESCRIPTION

FIG. 1 is a front elevation view of a pole mounted lantern in accordance with our invention;

FIG. 2 is a rear elevation view thereof;

FIG. 3 is a left side elevation view thereof, the right side elevation view being a mirror image thereof; and,

FIG. 4 is a bottom plan view thereof.

The broken lines illustrate portions of the pole mounted lantern and form no part of the claimed design.
